CLAIM

The ornamental design for a refreezable container, as shown and described.

DESCRIPTION

FIG. 1 is a perspective view of a refreezable container according to a first preferred embodiment of our new design; FIG. 2 is a top plan view of the refreezable container of FIG. 1;

FIG. 3 is a front elevational view of the refreezable container of FIG. 1, the rear elevational view and the left and right side elevational views being the same;

FIG. 4 is a bottom plan view of the refreezable container of FIG. 1;

FIG. 5 is a perspective view of a refreezable container according to a second preferred embodiment of our new design;

FIG. 6 is a top plan view of the refreezable container of FIG. 5;

FIG. 7 is a front elevational view of the refreezable container of FIG. 5, the rear elevational view and the left and right side elevational views being the same; and,

FIG. 8 is a bottom plan view of the refreezable container of FIG. 5.
